UNITED STATES PATENT OFFICE

JOHN W. ALLEN, OF FRESNO, CALIFORNIA

ADVERTISING DEVICE

Application filed May 20, 1930. Serial No. 454,041.

This invention relates to a device designed primarily for advertising purposes, the object of the invention being to provide means for attracting the attention of persons passing near the device, to the end that the advertising matter arranged on the device, will be readily observed.

An important object of the invention is to provide a device of this character which may 10 be supported in any convenient location on a motor vehicle, or on a stationary supporting structure, or may be carried in the hands of a person.

Another object is to provide a device of 15 this character including a disk-like body portion having openings, and a movable member operating at the rear of the openings, the movable member having colored portions to be viewed through the openings, to attract 20 the attention of persons passing near the device.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made 30 within the scope of what is claimed, without departing from the spirit of the invention.

Referring to the drawing:

Figure 1 is an elevational view of an advertising device constructed in accordance with 35 the invention.

Figure 2 is a side elevational view thereof.

Figure 3 is a rear elevational view of the device.

Referring to the drawing in detail, the 40 device comprises a disk-like body portion indicated by the reference character 5, the same being provided with openings 6 disposed adjacent to the edges thereof, the openings being rectangular in formation so that an 45 appreciable length of the bar 7, that op-

erates at the rear of the body portion 5, may be viewed therethrough.

The reference character 8 designates a support which may be in the form of a post or stick to be carried in the hand, the post 50 being provided with a pin 9 at its outer end, which pin secures the body portion 5 to the support 8.

This pin 9 also provides a bearing for the bar 7 that is formed with an opening to receive the pin, the opening being disposed intermediate the ends of the bar. The bar 7 is of a length to extend beyond the edge of the body portion 5, where it provides a support for the members 10 that extend at right angles 60 therethrough, the members 10 providing means whereby the pinwheels 11, may be secured thereto, the pinwheels being disposed beyond the body portion 5 so that they may rotate freely under wind pressure. 65

In order that the device will be exceptionally attractive, colored blocks 12 are positioned on the bar 7, at points where they may be viewed through the openings 6, with the result that the colors will change as the bar 7 70 revolves under the body portion 5.

The front surface of the body portion 5 is so constructed that advertising printed matter may be placed thereon, so that persons having their attention attracted by the pinwheels and changing colors, will readily see 75 the advertising matter on the body portion, to accomplish the purpose of the invention.

I claim:

1. An advertising device comprising a 80 disk-like body portion having openings extended therethrough, a bar mounted for rotary movement at the rear of the body portion and having colored portions to be viewed through the openings, rotary members operated by wind pressure, supported adjacent to the front surface of the body portion, a support for the body portion, and the front surface of the body portion adapted to receive printed matter. 85 90

2. An advertising device comprising a body portion having advertising matter on the front surface thereof, a bar rotatably mounted at the rear of the body portion, the
5 ends of the bar extending beyond the edge of the body portion, pinwheels mounted at the ends of the bar to operate at points adjacent to the front surface of the body portion, and means for supporting the body portion and
10 bar.

In testimony that I claim the foregoing as my own, I have hereto affixed my signature.

JOHN W. ALLEN.
